UNITED STATES PATENT OFFICE.

GEORGE S. BARKENTIN, OF NEW HAVEN, ASSIGNOR TO P. & F. CORBIN, OF NEW BRITAIN, CONNECTICUT.

DESIGN FOR A BRACKET.

SPECIFICATION forming part of Design No. 16,947, dated October 26, 1886.

Application filed May 24, 1886. Serial No. 203,080. Term of patent 7 years.

To all whom it may concern:

Be it known that I, GEORGE S. BARKENTIN, a citizen of the United States, residing at New Haven, in the county of New Haven and State of Connecticut, have invented and produced a new and original Design for Brackets, of which the following is a specification, reference being had to the accompanying drawing, forming part thereof, which represents said bracket in side elevation.

The leading features of my design consist of the cross-bar A, connecting the upper and lower arms of the bracket, as at a b. This cross-bar A is paneled and the groundwork roughened or filled with short transverse lines, as shown. The triangle inclosed by portions of the upper and lower arms and the cross-bar A is filled with incised lines, as at h, crossing each other at right angles, thus forming squares or sections thereof in relief, in the center of which are dots, as at i. Springing from the cross-bar A, and dependent therefrom, are two branches or vines, B B, having the conventional ivy-leaves, as at F, and the flower G. One of the branches B extends along in the direction of the upper arm of the bracket and partly fills the open rectangular panels inclosed by the bars j k l. The other branch B extends down-

ward in the direction of the lower arm of the bracket and partly fills the open rectangular panels inclosed by the connecting-bars j l m n o p. The outward angles formed by these connecting-bars are partly filled by the conventional ornament, as c, d, e, and f.

I claim--

1. The design for a bracket herein shown and described, the same consisting of the paneled cross-bar A, filled with transverse lines, and extending obliquely from the upper to the lower cross-arms, as at a and b, and the triangle thus formed having a general plain surface filled with regularly-spaced lines crossing each other at right angles, and the squares thus formed in relief having the central dots, i.

2. The design for a bracket herein shown and described, consisting of the rectangular open panels partly filled with the two branches or vines B B, springing from the cross-bar A, and extending along in the direction of the upper and lower arms, and having the conventional ornaments.

GEORGE S. BARKENTIN.
